UNITED STATES PATENT OFFICE.

THEODORE W. CASE, OF SCIPIO, NEW YORK.

RESISTANCE ELEMENT.

1,342,842.

Specification of Letters Patent. Patented June 8, 1920.

No Drawing.

Application filed March 15, 1920. Serial No. 335,898.

To all whom it may concern:

Be it known that I, THEODORE W. CASE, of Scipio, in the county of Cayuga, in the State of New York, have invented new and 5 useful Improvements in Resistance Elements, of which the following, taken in connection with the accompanying drawings, is a full, clear, and exact description.

This invention relates to a certain new and 10 useful variable resistance, and more specifically to a resistance element of that class, characterized by the fact that the resistance of the element to the passage of an electric current therethrough varies with variations 15 in intensity of the light rays to which the element is exposed.

The invention contemplates the production of a light sensitive element adapted to constitute a portion of an electric circuit, 20 subject to the condition that variations in intensity of the light rays to which the element is exposed produce a corresponding variation in the electrical resistance of the element, thereby effecting a variation of 25 electric current in the circuit in accordance with variations of light intensity to which the element is exposed.

I have discovered that a resistance element comprising or consisting of a compound of 30 thallium and bromin can be utilized as a portion of an electric circuit, and that its resistance to the passage of electric current through said circuit varies under the influence of light to effect a change of current 35 inversely in accordance with the intensity of light rays to which the substance is subjected. Further, thallium bromid is peculiarly efficient for this purpose, and highly sensitive to variations of light intensity, due 40 to the fact that the ratio of change or percentage change of its resistance to the passage of an electric current under variations of light intensity is great.

The material, compound or resistance ele-

ment may be incorporated in an electric circuit in any suitable way, and said element may constitute any portion or part of such circuit, and when so incorporated the element may be supported in any suitable way for contact and exposure to light rays. 45

The invention is adapted for and may be applied to various uses, as, for instance, in the Bell photophone, or the apparatus of my co-pending application, Serial No. 213,225, and I therefore desire to broadly 50 claim the same without restriction as to the method, manner or condition of use, and without limitation as to the addition of any other element or elements to the material or compound, so long as the same do not 55 destroy the utility of the material for the purpose described, and I desire to claim the material for use with either direct, pulsating direct, or alternating current.

The expression "light rays" as used in the 60 specification and claims hereof, is deemed to include all usable rays throughout the spectrum.

What I claim is:—

1. A resistance element formed of a compound of thallium and bromin. 70
2. A resistance element formed of a compound comprising thallium and bromin.
3. A resistance element formed of a material comprising a compound of thallium 75 and bromin.
4. An electric circuit having a portion supported for exposure to light rays, such portion comprising a compound of thallium and bromin. 80

In witness whereof I have hereunto set my hand this 10th day of March, 1920.

THEODORE W. CASE.

Witnesses:

EARL I. SPONABLE,
MAY F. GLEASON.
